CLAIM

The ornamental design for a male sanitary protector as shown and described.

DESCRIPTION

FIG. 1 is a top front side perspective view of a male sanitary protector showing my new design;

FIG. 2 is a front view of the male sanitary protector, a rear view being identical;

FIG. 3 is a right side view of the male sanitary protector, a left side view being identical;

FIG. 4 is a top view of the male sanitary protector; and,

FIG. 5 is a bottom view of the male sanitary protector. The broken lines show portions of the male sanitary protector that form no part of the claimed design.
